UNITED STATES PATENT OFFICE.

JOHN HANSEN, OF BETTENDORF, IOWA, ASSIGNOR TO DAVENPORT MANUFACTURING COMPANY, INC., OF DAVENPORT, IOWA.

POWER BALING MACHINE.

Application filed April 20, 1925. Serial No. 24,425.

My invention has reference to power bal-
ing machines, of that class shown in my
former application for Letters Patent of the
United States, filed January tenth, 1925,
Serial No. 1565, in which machines the
compression devices are operated by means
of a pair of vertical screws, rotatably sup-
ported at opposite ends of the machine.
Vertically movable on said screws are platen
supporting devices, said platen being mov-
able in a downwardly or upwardly direction
with said devices, the downward movement
thereof causing the platen to exert a pres-
sure upon the contents of the machine. In
machines of this kind, which are filled from
a point overhead, it is desirable to have the
platen mechanism arranged so as to clear
the top of the machine, so as to leave the
same completely open for the purpose of
receiving the material. This is accom-
plished in the machine mentioned by tipping
the platen to one side of the machine as it
nears the top thereof. This is brought about
by the cooperation of gear devices partly
stationed on the frame of the machine and
partly movable with the platen mechanism.
As a result the coacting gears are only in
mesh at the upper end of the platen move-
ment, such gears disengaging as the platen
moved downwardly, and re-engaging upon
the return thereof. It is therefore essential
that the gears be perfectly formed and posi-
tioned, so that they will mesh exactly, other-
wise there is danger of their jamming and
causing stoppage and breakage of parts.

In the present invention gearing is also
made use of to produce the desired results,
but this gearing is so arranged and operated
that the gears thereof are always in mesh,
so that there is no possibility of their being
or getting out of register. By reason there-
of the machine has a positive action and a
high degree of efficiency.

The particular construction, arrangement,
and operation of the various parts of the ma-
chine will be more fully understood from
the following specification, reference being
had to the accompanying drawings, in
which:

Fig. 1 is a view, partly in section, longi-
tudinally of the machine.

Fig. 2 is an end view thereof.

Fig. 3 is a horizontal section, on the
broken line 3-3 of Fig. 1.

Fig. 4 is an enlarged detail of the gear 55
segment 27.

Fig. 5 is a similar view of the gear seg-
ment 28.

Fig. 6 is an enlarged view of the platen
shifting devices, in operative position. 60

Fig. 7 is an enlarged sectional view of the
carrier 17 and appurtenant parts.

The reference number 1 indicates a frame,
supported on I-beams 2, the corner-posts of
said frame being united at their upper ends 65
by cross-pieces 3, preferably formed of
channel-plates. Said frames are further
braced by angle-plates 4, and are united by
longitudinal channel-plates 5. Supported
centrally of the machine is a receptacle, the 70
lower part of which is formed of a floor 6.
At one end thereof is a pair of end-plates
7, spaced apart at their inner edges, and
reinforced at said edges by angle-plates 8.
To the outer edges of the plates 7 are hinged
75 side-plates 9, having angular end-plates 9a,
also spaced apart at their inner edges, and
provided at said edges with angle-plates 10.
The construction of said receptacle is largely
similar to the present construction thereof, 80
and the same is not broadly involved in the
present application. The hinged side and
end plates are also adapted to be held in
closed position by means of suitable fasten-
ing devices on said end plates, as shown at 85
A in Fig. 2, said devices being adapted for
connection with parts of the frame above
and beneath said end plates.

Fixed on the inner faces of the cross-pieces
3 are bearings 11, in which are rotatably 90
supported screw-shafts 12, the lower ends
of which are journaled in bearings 13 in
the base of the frame. On the lower ends
of said shafts are yolute-gear wheels 14, en-
gaged by corresponding drive gears 15 on
a shaft 16, rotatably mounted in the base
of the machine. Power is imparted to said
shaft to rotate the same, the movement there-
of being communicated through said gear
devices to the screw-shafts 12, to give rota-
tion thereto, simultaneously, and in the
same direction. 95

On each of the screws 12 is a traveller 17,
internally threaded to correspond with the
threads on said screws, and movable vertical-
ly thereon upon the screws being rotated.
Supported on each of said travellers is a
yoke 18, from the inner faces of which 100
105

project stud-shafts 19, upon which are rockingly supported sleeves 20, at the ends of an arch-frame 21, to the lower face of which is fixed a platen or ram, preferably formed of 5 channel-plate sections 22, as shown in Fig. 1.

Near the lower end of one of the travellers 17 is an annular rib 24, and to the lower end of said traveller is fixed a collar 25, preferably by a threaded connection with the 10 traveller. Between said rib and collar is rotatably supported a plate 26, on one edge of which is a segmental bevel-gear 27, in mesh with a similar bevel-gear segment 28, fixed to lugs 29 on the sleeve 20. At the 15 opposite edge of the plate 26 is a follower 30, adapted for engagement with a track formed by a channel-plate 31, secured at its upper end to the cross-plate 3, and at its lower end to a block 32 on the inner face 20 of the cross-piece 4. Said track is formed of a lower vertical portion *a*, a spiral portion *b*, and an upper vertical portion *c*.

Upon the shafts 12 being simultaneously rotated the travellers 17 move upwardly or 25 downwardly thereon, depending upon the direction of rotation of the shafts, said travellers carrying with them the frame 21 and platform 22. During the greater part 30 of such movement the platen is held in a horizontal position by reason of the frame 21 being guided near its ends by the plates 8 at one end and the plates 10 at the other end, and upward extensions 34 and 35 of said plates.

35 In the upward movement of the platen, after it has fully cleared the receptacle for the material the follower 30 enters the track 31, and the parts continue to move upwardly until the arch 21 is clear of the guides 40 34 and 35, which diverge from each other in the upper part of the machine, forming braces for the upper ends of said guides. (Fig. 2.) As the upward movement of the travellers continues the follower 30 traverses 45 the spiral portion of the track 31, giving to the plate 26 and gear 27 thereon a rotary movement of approximately ninety degrees. This movement is imparted to the gear 28 in a corresponding degree, giving a quarter-50 turn to the sleeve 20, and tipping the platen 22 into a vertical position, as shown in Fig. 2. The follower 30 then moves upwardly in the track section *c* until the platen is well clear of the upper part of the receptacle. The movement of the driving 55 mechanism is then arrested, preferably by automatic means, as shown in said former application. The upper part of the receptacle is then fully cleared, to permit the introduction of material into the same.

60 Upon a reverse movement of the shafts 12 the follower 30 retraces its course through the track 31, restoring the gears 27 and 28 to their normal positions, and tipping the 65 platen back into a horizontal plane, suit-

able for operation on the material in the machine. It will be noted that said gears are always in engagement, ready to operate upon the proper impetus being given thereto.

70 What I claim, and desire to secure by Letters Patent, is:

1. A device of the class described, comprising a frame and receptacle therein, vertical screws rotatably mounted in the ends 75 of said frame, travellers on said screws, means for actuating said screws to cause a movement of the travellers upwardly thereon, or the reverse, a platen frame pivotally supported by said travellers, and provided 80 with compression devices, means for guiding said platen frame in the vertical movement thereof, to a point near the end of its upward movement, cooperating gears on one of said travellers and the platen frame, and 85 mechanism on the main frame for actuating the gear on the traveller to impart a partial rotation thereto, and to the cooperating gear, to convert the platen devices from a horizontal 90 to a vertical position, or the reverse. 95

2. A device of the class described, comprising a frame and receptacle therein, a screw device rotatably mounted in said frame and member, supported thereon so as to be vertically movable, upon said screw device being rotated, a platen mechanism supported by said member, so as to be capable of being tilted, to bring the platen from a horizontal to a vertical position, guiding means for 100 said platen to hold the same in a horizontal position until it nears the end of its upward stroke, cooperating gears on said movable member and the platen mechanism, and co-acting devices on said movable member and the frame, capable of giving a partial rotation to said movable member, coincidently with a continued vertical movement of the movable member, to impart a tilting movement to the platen mechanism. 105

3. A device of the class described, comprising a frame and receptacle therein, screw mechanism at the ends of said receptacle, including vertically movable carriers, a platen mechanism pivotally supported on 110 said carriers, guides for said platen mechanism capable of holding the same with the platen in a horizontal position in the vertical movement thereof to a point near the upper end of its movement, and disengaging therefrom at said point, a rotatable member on one of said carriers, provided with a cam follower, a cam track on said frame adapted for engagement by said follower, said track having a straight portion for initial engagement by said follower without actuating said 115 rotatable member, and a spiral portion for continued engagement with said follower to impart a partial rotation to said rotatable member, and means for imparting the movement of said rotatable member to said platen 120

mechanism, to rock the platen into a vertical position, the follower being fully engaged with said cam-track before said guides disengage from the platen mechanism.

- 5 4. A device of the class described, comprising a frame and receptacle therein, vertically movable supports at the ends of said receptacle, and means for imparting movement thereto in an upwardly or downwardly direction, a platen mechanism rockingly connected with said supports, guides for said platen mechanism adapted to hold the same with the platen in a horizontal position to a point near the end of its upward movement, 10 and disengageable therefrom at that point, a rotatable member on one of said supports, operatively connected with said platen mechanism so as to impart a rocking movement thereto, and provided with a cam engaging 15 device, a cam member fixed on said frame

adapted for engagement by said last-named device upon said platen mechanism nearing the end of its upward movement, said cam member having a straight track for initial engagement with said device without actuating said rotatable member, a spiral portion for secondary engagement with said device to give a partial rotation to said rotatable member, and a terminal straight track permitting a continued vertical movement of 20 said rotatable member without imparting rotation thereto, and means for imparting the movement of said rotatable member to said platen mechanism, to change the position of the platen with relation to said receptacle, 25 said guides coacting with said cam member and engaging device during a portion of the initial engagement of said parts.

In testimony whereof I affix my signature.
JOHN HANSEN.
